UNITED STATES PATENT OFFICE.

HARRY MINTZ, OF BOSTON, MASSACHUSETTS.

DESIGN FOR A HAMMOCK.

60,963.

Specification for Design.

Patented May 16, 1922.

Application filed September 17, 1921. Serial No. 501,463. Term of patent 7 years.

To all whom it may concern:

Be it known that I, HARRY MINTZ, a citizen of the United States of America, residing at Mattapan, Boston, in the county of Suffolk and Commonwealth of Massachusetts, have invented a new, original, and ornamental Design for Hammocks, of which the following is a specification, reference being had to the accompanying drawing, forming a part thereof.

In said drawing the figure is a perspective view of a hammock showing my new design.

I claim:

The ornamental design for a hammock substantially as shown.

Signed by me at Boston, in the county of Suffolk, and Commonwealth of Massachusetts, this 16th day of September, 1921.

HARRY MINTZ.
